UNITED STATES PATENT OFFICE.

HOWARD M. DUDLEY, OF PHILADELPHIA, PENNSYLVANIA.

HOSIERY-DYEING MACHINE.

1,344,120.

Specification of Letters Patent. Patented June 22, 1920.

Application filed June 5, 1918. Serial No. 238,298.

To all whom it may concern:

Be it known that I, HOWARD M. DUDLEY, a citizen of the United States, residing in the city of Philadelphia, county of Philadelphia, and State of Pennsylvania, have invented certain new and useful Improvements in Hosiery-Dyeing Machines, of which the following is a full, clear, and exact specification.

10 My invention relates to dyeing machines and refers particularly to machines suitable for the dyeing of hosiery and similar fabrics.

The object of my invention is a device in which hosiery and similar fabrics may be 15 dyed evenly and uniformly, which object is accomplished by a novel arrangement of foraminous chambers, through which the dyeing liquid may be so forced as to treat all portions of the fabrics equally.

20 My device comprises in a broad way a hollow foraminous reel carrying a series of dyeing chambers, all of the sides of which are foraminous, thus giving free access of the liquid equally throughout all of the chambers.

25 It also comprises means whereby easy access can be made to any of the chambers. It also comprises a smaller testing device, in which hosiery can be treated uniformly with the hosiery in the larger device, and which can 30 be removed from the liquid within the receptacle and examined without removing the liquid from the receptacle.

These and other accomplishments of my device will be evident upon a consideration 35 of my specification and drawings, in which similar parts are designated by similar numerals:

Figure 1 is a vertical cross-section of one form of my device.

40 Fig. 2 is a section through the line 2—2 of Fig. 1.

Fig. 3 is a section through the line 3—3 of Fig. 1.

Fig. 4 is a broken end plan view of a 45 portion of the reel and dyeing chambers showing the top in closed and opened positions.

Fig. 5 is a top plan development of Fig. 4.

Fig. 6 is an enlarged broken vertical section of the testing device taken through the line 6—6 of Fig. 8.

Fig. 7 is a top plan view of Fig. 6.

Fig. 8 is a section through the line 8—8 of Fig. 6.

The particular form of the device of my 55 invention shown in the accompanying drawings, comprises a liquid receptacle formed by the sides 10, 11, 12, 13, the bottom 14 and the top 15 hinged to the side 11 at 16 and capable of being clamped in a closed 60 position to the side 13 by means of the wing bolt 17. An annular track member 18 is supported within the receptacle on the side 10 by means of the brackets 19, 19. A corresponding annular track member 20, in 65 horizontal alignment with the member 18, is attached to the side 12 by means of the brackets 21, 21.

Within the liquid receptacle is a revolvable reel comprised of the two end flanges 22 70 and 23, connected together by the foraminous cylinder 24. Fixedly attached to the foraminous cylinder 24 and extending outwardly therefrom is a series of foraminous plates 25, 25, the end edges of which abut 75 upon the flanges 22 and 23. A rock shaft 26 extends across the reel above each member 25 and is revolvable in the flange members 22 and 23. Fixedly attached to each rock-shaft 26 is a series of parallel members 80 27, 27 supported together by supporting bars 28, 28, so positioned that when a series of parallel members 27, 27 is closed inwardly of the reel it forms a foraminous top for a fiber chamber comprising a portion of the 85 foraminous cylinder 24 and two foraminous members 25, 25. The device as illustrated, therefore, contains six fiber chambers. In order to lock the fiber chamber top in a closed position, each side carries a locking 90 member 29, held in slidable position by means of the bolt 30 extending through the opening 31 of the member 29. The member 29 may be held in a non-slidable position by means of the wing-bolt 32. One end of 95 each member 29 has the extended arm 33 which can be slid under the rock-shaft 26, the handle 50 facilitating the operation, thus holding the top in a closed position.

The bars 27, 27 have their inner faces 100 serrated at 34.

The members 25, 25 have openings 35, 35.

The foraminous cylinder 24 comprises a series of spaced parallel diamond-shaped bars 36, 36.

One end of the foraminous cylinder 24 105 abuts upon the imperforate flange 22, while the interior of the cylinder is extended into

the outwardly extended conical member 37 of the flange 23, which is further extended into the pipe 38 which is connected to a means as a pump, not shown, for forcing liquid therethrough. The pipe 38 is revoluble within the bushing formed by the extension 39 of the side 10 and the bushing member 40. The flanges 22 and 23 have a series of extended brackets 41, 41, the outer portions of which are extended into the annular track members 42, 42 and 43, 43. Between the track members 42 and 20, and between the track members 43 and 20 and between 42, 43 and 18, are two series of ball bearings 44, 44 running in suitable runways.

A cogged wheel 45 fixedly attached to the revoluble shaft 46, extends through the top 15 and meshes with cogs upon the outer periphery of one of the track members 42.

20 A drain pipe 47, carrying the valve 48, opens into the liquid receptacle. The liquid receptacle also carries an overflow pipe 49.

A removable testing device comprises the side members 60, 61, 62, 63, the foraminous bottom 64 similar to the foraminous cylinder 24 and a top 65 attached to the side members by means of screw bolts 66, 66, 66. The top has a number of openings 67, 67. A foraminous cover 68 to the fiber chamber is similar in general construction to one of the covers in the larger device. The member 37 has outwardly extended members 69, 69 into which the sides 62, 63 of the testing device will fit, an opening 70 of the member 37 corresponding to the foraminous plate 64. The top 65 has an extended portion 71 through which there is a slidable pin 72 capable of insertion with in the hole 73 of the flange 23. A spiral spring 74 abuts upon the member 71 and the collar 75 of the pin 72. Pivotaly attached to the one end of the pin 72 is a double elbow link 76, which is revoluble upon the pin 77 carried by the bearing 78 upon the top 65. The member 76 is extended upwardly until it is above the liquid within the liquid receptacle, and has a hole 79 for the insertion of a hook 80. A member 81 of the flange 23 serves as a 50 guide for the proper movement of the testing device. A stop-block 82 limits the movement of the pin 72.

From the above described construction it is seen that when the testing device is in its operative position, as shown in Figs. 6, 7 and 8, it is maintained in that position by means of the pin 72 within the hole 73. When it is desired to examine the contents of the testing device, it is not necessary to withdraw the liquid from the receptacle, but by pulling upward upon the extended portion of the link 76, the pin 72 is withdrawn from within the hole 73 and the entire testing device may be withdrawn, the top 65 removed, the contents examined, the top

replaced and the device lowered into place, the release of the link 76 allowing the pin 72 to enter the hole 73.

The operation of the device is as follows:

The top of each one of the fiber compartments is opened after removing the gear 45 and the shaft 46, the necessary quantity of hoisery, or other fiber material, introduced and the top closed and locked. When all of the fiber chambers and the testing device contain the fiber, the gear 45 and the shaft 46 are replaced and the reel, its contents and the testing device are revolved and the desired liquid introduced through the members 38 and 37 into the interior of the reel, whence it passes through the foraminous cylinder 24 into all of the fiber chambers and then outwardly through the foraminous tops into the receptacle and then through the overflow pipe 49 back for continuous circulation. At the same time the liquid passes through the opening 70 into the testing device and through the same.

I do not limit myself to the particular size, shape, number or arrangements of parts described and shown, all of which may be varied without going beyond the scope of my invention as described and claimed.

What I claim is:-

1. In a dyeing machine, in combination, a receptacle, a hollow revoluble foraminous cylinder within the receptacle; means for revolving the cylinder; two imperforate end flanges carried by the cylinder forming a reel therewith; a series of foraminous plates carried by the cylinder and longitudinal thereof, said plates abutting upon the end flanges; a removable foraminous cover for each fiber chamber formed by the cylinder, the foraminous plates and the flanges; and means exterior of the receptacle for the continuous forcing of a liquid through the device.

2. In a dyeing machine, in combination, a receptacle, a hollow revoluble foraminous cylinder comprising a series of spaced parallel extended members within the receptacle; means for revolving the cylinder; two imperforate end flanges carried by the cylinder forming a reel therewith; a series of foraminous plates carried by the cylinder and longitudinal thereof, said plates abutting upon the end flanges; a removable foraminous cover for each fiber chamber formed by the cylinder, the foraminous plates and the flanges; and means exterior of the receptacle for the continuous forcing of a liquid through the device.

3. In a dyeing machine, in combination, a receptacle, a hollow revoluble foraminous cylinder within the receptacle; means for revolving the cylinder, two imperforate end flanges carried by the cylinder forming a

reel therewith; a series of foraminous plates carried by the cylinder and longitudinal thereof; said plates abutting upon the end flanges; a removable foraminous cover for each fiber chamber formed by the cylinder, the foraminous plates and the flanges and a pump means whereby all of the liquid passing through the cylinder will be forced through the fiber chamber and the foraminous covers.

4. In a dyeing machine, in combination, a receptacle, a hollow revoluble foraminous cylinder comprising a series of spaced parallel extended members within the receptacle; means for revolving the cylinder; two

imperforate end flanges carried by the cylinder forming a reel therewith; a series of foraminous plates carried by the cylinder and longitudinal thereof, said plates abutting upon the end flanges; a removable foraminous cover for each fiber chamber formed by the cylinder, the foraminous plates and the flanges and a pump whereby all of the liquid passing through the cylinder will be forced through the fiber chambers and the foraminous covers.

Signed at New York, in the county of New York and State of New York, this 20th day of April, 1918.

HOWARD M. DUDLEY.
